UNITED STATES PATENT OFFICE

WILLIAM P. BEATTIE AND JOSEPH B. SANDO, OF NORWOOD, OHIO, ASSIGNEES TO THE AMERICAN LAUNDRY MACHINERY COMPANY, OF CINCINNATI, OHIO, A CORPORATION OF OHIO

REVERSING DRIVE

Application filed October 15, 1931. Serial No. 569,008.

Our invention relates to driving mechanism and, particularly, to a reversing fluid operated driving mechanism especially applicable to laundry machinery wherein parts, 5 for instance the cylinder, are rotated first in one direction and then in the other. We have shown and hereinafter describe the driving mechanism as applied to a washing machine in which the reversing operation is 10 characteristic although the driving mechanism is equally applicable to many other types of machinery.

Heretofore, the cylinder or clothes containing member of a washing machine has 15 ordinarily been driven by an electric motor through a system of belting or gearing with the cylinder rotating a given number of revolutions in one direction and then reversing to rotate a given number of revolutions in 20 the opposite direction. The type of drive used required a corresponding number of reversals of the electric driving motors which have necessarily been designed to withstand such frequent reversals. Aside from the expense of special construction, current costs 25 are quite an important factor when electric motors are frequently reversed.

Our invention contemplates a driving mechanism in which a uni-directional motor 30 drives a fluid pump connected through a rotary valve to a reversing fluid motor which drives the cylinder or clothes container of the laundry apparatus by direct connection, the rotary valve being driven through a reduction gearing by the uni-directional motor. In our construction, a single valve is located 35 in the feed line between the pump and rotary valve, the single valve being connected to an operator-operated means that takes 40 the form of a hand lever near the front of the machine by which starting, stopping, inching, or complete control is accomplished without interfering with continuous operation of the electric motor.

45 In addition to the decreased operating costs

resulting from the above type of apparatus, there are other advantages which include, accomplishing zero to maximum speed of the cylinder without intermediate control, uniform acceleration, elimination of noise of 50 heavy gearing, and greater flexibility in operation. With our type of drive, a plurality of machines may be operated by one unit embodying a single electric motor and single pump arranged in a location to conserve 55 floor space. The use of a single motor has the advantage of eliminating current surges and line disturbances resulting from the use of a number of motors on the same current line.

Various objects and other advantageous features of our invention may be seen in the following description and one embodiment thereof may be seen in the accompanying drawings wherein similar characters of reference designate corresponding parts, and 60 wherein:

Fig. 1 is an end elevation of a washing machine equipped with a drive mechanism embodying our invention; Fig. 2 is a plan 70 view of the drive mechanism shown in Fig. 1, the drive mechanism being likewise attached to a washing machine; Fig. 3 is a sectional view taken on the line 3--3 of Fig. 2 showing one position of the valve member during forward rotation of the washing machine cylinder; Fig. 4 is a view similar to Fig. 3 showing the valve member advanced in its rotation to a position which would correspond to a period 75 in the operation of the washing cylinder where it has stopped just prior to reversal of rotation thereof; Fig. 5 is a view similar to Figs. 3 and 4 showing the valve member further advanced at which time the cylinder is rotating in a reverse direction; Fig. 6 80 shows the valve member advanced to a position 90° further in its rotation from the position shown in Fig. 4 and which position, like Fig. 4, would correspond to a period in the 85 operation of the washing cylinder where it 85

has stopped just prior to reversal of rotation thereof; Fig. 7 is a sectional view taken on the line 7—7 of Fig. 6 showing one construction of the rotary valve; Fig. 8 is a sectional view taken on the line 8—8 of Fig. 1, showing the valve gate in a position wherein the main port is closed and the by-pass port is open for operation of a cylinder braking mechanism; Fig. 9 is a view similar to Fig. 8 with the valve gate in position such that the main port is opened and the by-pass port is closed for operation of the cylinder; Fig. 10 is a sectional view on the line 10—10 of Fig. 8; and Fig. 11 is a sectional view of the brake operating cylinder.

Referring to the drawings, I have shown a washing machine of a more or less standard construction comprising an end head 1 carrying a bracket 2, outside casing 3 and a rotatable cylinder 4. A well known type of reversing fluid operated motor 5 is carried by the bracket 2 and directly connected to a gudgeon 6 of the cylinder 4 by a suitable coupling 7.

25 A bracket 8 is mounted at the rear of the washer casing 3 to provide a support for a standard uni-directional electric motor 9 directly connected to a well known type of centrifugal pump 10 by means of a coupling 11. 30 Another bracket 12 on the end head 1 supports a rotary valve 13, the bracket being provided with upwardly extending flanges for the support of shaft supporting bearings 14 and 15. A bevel gear 16 is securely mounted 35 on the motor shaft 17 and meshes with a bevel gear 18 secured to a shaft 19 supported in a bearing 20 that is mounted on the bracket 8. The shaft 19 has a worm 21 on one end thereof which meshes with a worm gear 22 that is 40 securely mounted on the shaft 23 of the rotary valve 13 between the shaft supporting bearings 14 and 15. With this construction, the continuously operating uni-directional motor 9 will continuously operate the rotary 45 valve 13.

For conveying operating fluid from the pump 10 to the fluid motor 5, a supply conduit 24 connects the pressure side of the pump 10 with the inlet port 25 of the rotary valve 13. 50 Another conduit 26 leads from a port 27 in the rotary valve to the forward connection 28 of the fluid motor 5. A conduit 29 connects a port 30 in the rotary valve with the rearward connection 31 of the fluid motor 5. 55 and a return conduit 32 leads from a return port 33 in the rotary valve to the suction side of the pump 10.

Referring to Figs. 3-7 inclusive, the rotary valve 13 consists of a cylinder 34 having one end thereof threaded as at 35 and adapted to receive a threaded cap 36 which fits within the hollow end of the casing 34 and abuts against a shoulder 37. A ring gasket 38 may be provided to form a seal. The valve member itself consists of end flanges 39 and 40

connected by a web 41, the valve member being connected to the shaft 23 extending through a packing gland 42 in the cap member 36 whereby the valve member may be rotated by the operation of the motor 9.

It will be noted that the outer edges 43 and 44 of the web 41 are wider than the central section, these widened portions being adapted to engage the inner wall of the cylinder 34 and provide a means for closing the ports 25, 27, 30 and 33. The width of the outer edges 43 and 44 is slightly in excess of the port openings whereby the edges will completely close off such openings and for other reasons hereinafter described.

80 Suitable means are provided for controlling the flow of fluid through the rotary valve 13 and thereby control the operation of the cylinder 4. This means consists in a control valve 45 disposed in the pressure conduit 24 with an operating lever 46 therefor connected by means of a rod 47 to a hand control lever 48 pivotally mounted as at 49 to the end head 1. This hand lever 48 is adapted to 85 slidably engage an arc-shaped boss 50 on the end head 1 of the washer, the arc-shaped boss being provided with spaced perforations 51 adapted to receive a spring-pressed pin operated by a trigger 51' of the lever 48 to hold the hand lever 48 in one of its respective positions.

Four perforations 51 are shown in the present instance which are spaced to represent "brake application", "pressure off position", "intermediate speed position", and "high speed position." For example, when the hand lever 48 is in the position shown in Fig. 1, the braking means hereinafter described has been applied and the cylinder is inoperative. Upon movement of the lever to the next position, the braking means is released with the cylinder still remaining inoperative, this being a neutral position at which pressure has not been admitted to the rotary valve 13. When the lever 48 is moved to the third position, the cylinder 4 will operate at a slow speed, or that speed most adaptable to the treatment of blankets, woolens, and the like, and, when the lever 48 is moved to the last position, the cylinder will operate at a speed at which the general class of materials are treated. This variation in speed need not be limited to the four positions shown. That is, the arc-shaped boss 50 may be provided with any number of perforations 51 for any number of desired speeds.

110 The control valve 45, shown in Figs. 8, 9 and 10, is of the gate type and is provided with a main port 52 and a by-pass port 53, a gate 54 being pivoted as at 55 and so designed as to cover and prevent flow of fluid through either port when in the dotted line position as shown in Fig. 8, which position it assumes when the hand lever 48 is opposite the second perforation representing the 115 120 125 130

"pressure off" position. This position has been provided for emergency and has other advantages as when a free moving cylinder, not under control of the fluid motor nor restricted by a brake, is desired. In this event, some means such as a relay mechanism may be provided for stopping operation of the motor 9 and pump 10. Movement of the hand lever to the first position causes the 5 gate 54 to move clockwise as shown by the full lines in Fig. 8 which, while covering the main port 52, uncovers the by-pass port 53 to admit fluid pressure from the pump 10 through a conduit 56 to a brake cylinder 57 which applies the brake and prevents movement of the cylinder 4.

Movement of the hand lever 48 to the third position representing "intermediate speed" causes the gate 54 to be rotated counter-clockwise about the pivot 49 to close the by-pass port 53 and partially open the main port 42 as shown by the dotted lines in Fig. 9. Further movement of the hand lever 48 to the fourth and last position shown representing "high speed" causes the gate to be moved to its limit in a counter-clockwise direction to completely uncover the main port 52 while keeping the by-pass port 53 covered. It will be noted that the ports 52 and 30 53 are never open simultaneously. Thus, the port 53 is closed before the port 52 has begun to open and the brake will not be applied with pressure at the motor 5 nor will the motor be started until the brake is released.

The brake 58 is represented as of the contracting bands type with the bands being adapted to engage a drum mounted on the gudgeon shaft 6 and, as shown in Fig. 11, 40 the brake is operated by fluid pressure admitted through the conduit 56 to the cylinder 57 which causes the piston 59 to move forwardly against the pressure of a spring 60 and rotate a lever 61 clockwise about its 45 pivot 62 to cause contraction of the brake band. As shown, the cylinder 57 is provided with a constant leak through a conduit 63 which leads to the fluid pressure conduit 32 and thence to the suction side of the 50 pump. This conduit is of a size as not to affect the operation of the brake during the application period when the by-pass port 53 is open and provides a quick relief for release of the brake when the by-pass port 53 is closed. Likewise, the conduits 56 and 63 55 may be of a size to permit sufficient fluid to by-pass around the rotary valve 13 when the brake is applied to prevent an undesirable amount of drag on the motor 9 by pressure built up in the line by the pump 10, although the centrifugal pump is preferably so 60 designed that after maximum pressure is reached the power required drops off making it impossible to overload the pump.

65 In the operation of this apparatus, assum-

ing the washing cylinder 4 to have been loaded and the proper supplies introduced into the washing machine for the first cycle of operation, the operator starts the electric motor 9 by any suitable means, for instance by 70 means of a push button switch 64, it being likewise assumed that the hand lever 48 is in the forward or "brake" position as shown in Fig. 1. The electric motor 9 and pump 10, as well as the rotary valve 13 rotate continuously in one direction through the bevel gears 17 and 18, the worm 21, and the worm gear 22.

Then, the operator moves the hand lever 48 rearwardly to the third or fourth perforation in the arc 59, dependent upon the speed desired, which rotates the gate 54 of the valve 45 to the dotted or full line position shown in Fig. 9 to close the by-pass port 53 and open the main port 52 whereupon the brake will be released by leakage of pressure through the conduit 63 to the fluid pump 10 and fluid pressure will be admitted through the conduit 24 to the rotary valve 13.

Assuming, that upon operation of the hand lever 48, that the valve member 41 is in a position for its rotation, which is always clockwise, as shown in Fig. 3. Then, fluid under pressure passes through the valve in the direction of the arrows from the port 25 and through the port 27 to the forward connection 28 of the fluid motor 5, through the fluid motor, and then returns by way of conduit 29, ports 30 and 33 of the rotary valve, 95 and conduit 32 to the pump 10 whereupon the fluid motor 5 and washing cylinder 4 will be rotated in a forward direction which will continue until the valve member 41 has rotated to the position shown in Fig. 4.

As shown in Fig. 4, it will be noted that the engaging edges 43 and 44 are wider than the port openings. This overlap provides sufficient time to allow the inertia of the rotating mass to be absorbed and the cylinder to come to a stop or to a speed slow enough to prevent shock when reversely flowing fluid pressure is admitted to the motor.

The valve member 41 continues to rotate 110 in the same direction until it opens the port 25 to the port 30 (see Fig. 5) whereupon fluid pressure is admitted to the fluid motor 5 through conduit 29 and the reverse connection 31, the fluid traveling through the motor and returning by way of conduit 26, through the rotary valve casing, and through conduit 32 to the suction side of the pump 10. The fluid motor 5 and the washing cylinder 4 are now rotating in the reverse direction from that previously described which 115 rotation will continue until the valve member 41 reaches the position shown in Fig. 6 where the flow to either side of the motor 5 is closed whereupon the motor 5 and the cylinder again stop prior to rotating in the 120 125 130

opposite direction. This cycle is repeated and the operation continues throughout the fabric treating period.

When it is desired to stop operation of the cylinder at the end of a treating period, the operator moves the hand lever 48 to the foremost position of the arc as shown in Fig. 1. This operation rotates the gate 54 of the valve 45 clockwise to first close the main port 52 and cut off the supply of fluid from the pump to the rotary valve and then opens the by-pass valve 53 whereupon fluid from the pump is admitted to the brake cylinder 57 to apply the brake and is then bypassed to the pump 10 around the rotary valve 13.

The electric motor, pump, and rotary valve operate continuously throughout the fabric treating period and movement of the machine during the various cycles of the treating period is accomplished solely through the control valve 45. Thus, if it is desired, the operation of the electric motor, pump, and rotary valve need not be interrupted throughout the entire day's operation. The arrangement is such as to prevent any possibility of dead-point positions of the rotary valve in the operation of the machine inasmuch as the rotary valve is driven directly by the prime mover or electric motor.

Assuming that the cylinder 4 has stopped at a point where the cylinder doors are not in registration with the doors in the casing 3, means have been provided for an operation known as inching to bring the doors into alignment. The outer casing door being opened, the operator moves the hand lever 48 rearwardly just slightly beyond the pressure off position whereby the cylinder will rotate slowly to bring the cylinder and casing doors into alignment at which time the lever 48 may be moved to braking position and the cylinder stopped.

With the above construction, we have provided a driving mechanism including a unidirectional prime mover adapted to effect operation of a motor unit of the reversing type together with operative connections therebetween and a single control mechanism effective to efficiently operate the reversing motor unit in any manner desired. The advantages of this drive unit will be readily apparent.

What we claim is:

1. Operating mechanism for apparatus of the character described, comprising a continuously operating pump, a motor, fluid connections between said pump and said motor, a timed reversing valve in said connections, means for by-passing the fluid from said pump past said valve, and fluid operated braking means in said by-pass.

2. Operating mechanism for apparatus of the character described, comprising a continuously operating pump, a motor, fluid con-

nections between said pump and said motor, a timed reversing valve in said connections, means for by-passing the fluid from said pump past said valve, a fluid operated braking means in said by-pass, and means in said connections for controlling the flow of fluid to said motor and through said by-pass means.

3. Apparatus for operating a washing machine cylinder comprising a fluid motor in driving relation with the cylinder, a continuously operating fluid pump, fluid connections between said pump and said motor and including timed valve means for periodically reversing said motor, operator-controlled valve means for controlling the driving connection between said pump and said motor, brake means for said cylinder, a fluid pressure actuator for said brake means, and connections for said actuator from the pump output including a brake control valve.

4. Apparatus for operating a washing machine cylinder, comprising a fluid motor in driving relation with the cylinder, a continuously operating fluid pump, fluid connections between said pump and said motor and including timed valve means for periodically reversing said motor, operator-controlled valve means for controlling the driving connection between said pump and said motor, brake means for said cylinder, a fluid pressure actuator for said brake means, connections for said actuator from the pump output including a brake control valve, and means interassociating said brake valve with said operator-controlled valve for common operator control.

5. Apparatus for operating a washing machine cylinder, comprising a fluid motor in driving relation with the cylinder, a continuously operating fluid pump, fluid connections between said pump and said motor and including timed valve means for periodically reversing said motor, operator-controlled valve means for controlling the driving connection between said pump and said motor, brake means for said cylinder, a fluid pressure actuator for said brake means, connections for said actuator from the pump output including a brake control valve, and means interassociating said brake valve with said operator-controlled valve for common operator control, said interassociating means providing that brake application cannot be coincident with drive of said cylinder.

6. Apparatus for operating a washing machine cylinder comprising a fluid motor in driving relation with the cylinder, a continuously operating fluid pump, fluid connections between said pump and said motor and including timed valve means for periodically reversing said motor, operator-controlled valve means for controlling the driving connection between said pump and said motor, brake means for said cylinder,

a fluid pressure actuator for said brake means, connections for said actuator from the pump output including a brake control valve, means interassociating said brake valve with said operator-controlled valve for common operator control, and means providing a connection from said brake actuator to the inlet side of said pump.

In testimony whereof we hereby affix our
10 signatures.
